BAIL EAR AND BODY BLANK ASSEMBLY

John Henchert, River Forest, Ill., assignor to Continental Can Company, Inc., New York, N.Y., a corporation of New York

Original application September 26, 1955, Serial No. 536,655, now Patent No. 2,905,124, dated September 22, 1959. Divided and this application April 13, 1959, Serial No. 805,846

5 Claims. (Cl. 220—91)

Paint cans, painters' buckets and other sheet metal containers of the bucket type have long been equipped with ears for the attachment of carrying bails, and the present invention relates to the attachment of such ears to the body blanks from which the side walls of the containers are to be formed.

This application is a division of my copending application for U.S. Letters Patent Serial Number 536,655 filed September 26, 1955 and entitled Method of Attaching a Bail Ear, now Patent No. 2,905,124 granted Sept. 22, 1959 and it covers the body blank and bail ear assembly disclosed in said copending application, whereas said copending application covers the method of attaching a domed sheet metal bail attaching ear to a sheet metal body blank.

The ears are formed of generally dome shape and each ear is provided at its base edge with an external, peripheral tubular bead. Each body blank is provided with a continuous wall for close concentric relation with the tubular bead of the associated domed ear. The domed beaded ear and blank are relatively assembled and the tubular bead and continuous wall placed in the aforesaid close concentric relation, and said tubular bead is then flattened in a direction to increase the radial dimension of said bead and force it into interlocking engagement with said continuous wall.

The above mentioned continuous wall may be cylindrical and when in this form it becomes deformed under the pressure exerted against it by the bead during flattening of the latter, thereby producing the desired interlocking relation of the wall and flattened bead. However, the wall may be preformed in the shape into which the aforesaid cylindrical wall will be deformed by the bead pressure, and the bead will then engage the pre-formed wall when said bead is flattened. In either instance, the bead presents a rounded edge to the wall with no danger of rupturing the latter. Moreover, in either case, the connection of the domed ear to the body blank is effected without the necessity of clinching the continuous bead engaging wall over the bead.

The aforesaid continuous bead engaging wall is preferably the side wall of a shallow recess formed by depressing a portion of the body blank, and the bottom of this recess is preferably formed with a boss which prohibits contraction of the bead radially of the domed ear during the bead flattening operation, thereby insuring forcible radial expansion of said bead into extremely tight interlocking engagement with said wall.

With the above and other objects in view that will hereinafter appear, the nature of the invention will be more clearly understood by reference to the following detailed description, the appended claims and the several views illustrated in the accompanying drawings.

In the drawings:

Figure 1 of the accompanying drawings is a side elevation showing a paint or similar can provided with bail ears in accordance with the present invention.

Figure 2 is an enlarged sectional view showing the

2

preferred domed and beaded ear initially assembled with a recessed body blank in readiness for bead flattening to unite ear and blank.

Figure 3 is a view similar to Figure 2 showing the bead flattened and the previously cylindrical recess side wall deformed into interlocking engagement with the flattened head.

Figures 4 and 5 are views similar to Figures 2 and 3 respectively but showing a construction in which the bead is formed by inward instead of outward curling of the base edge of the domed ear.

Figure 6 is a detail section of a portion of the recessed body blank showing that the boss on the recess bottom of the preceding views may be omitted.

Figures 7, 8, 9, 10 and 11 correspond to Figures 2 to 6, respectively, but disclose constructions in which the recess side wall is pre-shaped to engage the flattened bead.

In Figure 1, a conventional paint can 1 has been shown, said can having domed ears 2 secured thereto, in accordance with the invention, for the attachment of a carrying bail 3. All other views show one of the domed ears 2 and a portion of the body blank 4 from which the can wall is to be formed, in the positions which they preferably occupy during assembly, prior to shaping said body blank into can wall form.

In all examples of the invention herein disclosed, the sheet metal domed ear 2 is formed at its base edge with a continuous, external, tubular head 5, and the side wall 6 of said domed ear is preferably of cylindrical form.

30 In Figures 2 and 7, the bead 5 is formed by an outward curl 7, whereas in Figures 4 and 9 the metal is first turned outwardly at 8 and then inwardly curled at 9.

The sheet metal body blank 4, in all forms of the invention disclosed, is formed with a depressed portion 10 providing it with a shallow recess 11, said recess having a bottom 12 and a continuous side wall 13. The bottom 12 is formed with a boss 14 in all views except Figures 6 and 11, said boss being in concentric relation with the recess side wall 13. This recess side wall 13 is of an internal diameter slightly greater than the beaded end of the domed ear 2 and the external diameter of the boss 14 corresponds to the internal diameter of the beaded ear side wall 6.

In Figures 2, 4 and 6 the recess side wall 13 is of cylindrical form and becomes deformed to the downwardly flared shape of Figures 3 and 5 under the pressure exerted by the bead 5 during deforming of said bead into the flat shape shown at 15. In Figures 7 to 11, however, the recess side wall 13 is pre-shaped into acute angular relation with the recess bottom 12, giving it the same initial shape as the final shape of the cylindrical recess side wall. In either instance, a curved fillet 16 joins the recess side wall 13 and bottom 12, and another curved fillet 17 joins the boss 14 to said bottom 12.

55 In all cases in which the boss 14 is provided, the fillet 17 engages the inner periphery of the bead 5 when the ear 2 and blank 4 are brought into initially assembled relation. See Figures 2, 4, 7 and 9. The ear 2 is thus accurately positioned with its bead 5 resting evenly upon the recess bottom 12 in closely spaced concentric relation with the recess side wall 13. With the ear 2 and blank 4 thus initially assembled, the bead 5 is flattened by means of a press, one member of which is shown in broken lines at 18 in Figures 3, 5, 8 and 10.

65 During bead flattening, if the recess side wall 13 be cylindrical as in Figures 2, 4 and 6, the radial expansion of the bead 5 caused by said flattening, exerts such pressure against said wall 13 as to flare the latter to the shape of Figures 3 and 5, thus tightly interlocking said side wall 13 with the flattened bead 15. If the recess side wall 13 be pre-flared as in Figures 7 to 11, flattening of the bead 5 (Figures 8 and 10) causes the flattened bead 15 to in-

terlock tightly with said wall 13 but produces no further appreciable deformation of the latter. In either case, the union of ear 2 and blank 4 is effected without danger of puncturing or otherwise rupturing any portion of the blank 4, as the bead 5 has only smooth surfaces contacting with said blank. More over, the union is highly effective without requiring that the recess side wall be clinched over the flattened bead. It will be apparent by reference to Figures 3, 5, 8 and 10 of the drawings that in each instance the flattening of the tubular bead results in the provision of a doubled wall fold and the forcing thereof outwardly against the surrounding side wall defining the depressed portion 10.

In any form of the invention in which the boss 14 is employed, this boss holds the bead 5 against any contraction radially of the ear 2, during the bead flattening operation, thus increasing the radial expansion of said bead into extremely tight interlocking relation with the recess side wall 13.

In the completed structure (Figures 3, 5, 8 and 10) the transversely curved outer edge 19 of the flattened bead 15 tightly engages the fillet 16 but may yield slightly thereon during curving of the body blank 4 into cylindrical shape to form the container side wall. The union of ear 2 and blank 4 will not therefore interfere with this operation and a truly cylindrical shape may be imparted to the container side wall.

From the foregoing it will be seen that novel and advantageous provision has been disclosed for attaining the desired ends. However, attention is invited to the possibility of making variations within the scope of the invention as claimed hereinafter.

I claim:

1. In a body blank and bail ear assembly, a sheet metal body blank having a depressed portion providing a shallow external recess, said recess having a bottom and a continuous side wall at an acute angle to said bottom, and a domed sheet metal bail ear, said domed bail ear having a flattened tube bead on its base and seated upon said bottom, said flattened bead having a doubled fold wall providing a transversely curved peripheral edge seated in the angle between said bottom and side wall, thereby tenaciously connecting the domed ear to the body blank with no danger of said bead edge cutting the blank

portions contacting therewith, and establishing this connection without the necessity of inwardly clinching any portion of said side wall over said bead.

5. A structure as specified in claim 1 in which said depressed portion of said body blank is provided with a curved fillet at the juncture of said bottom and side wall, said fillet conforming to and tightly contacting with said doubled fold wall transversely curved peripheral edge of said flattened bead.

10 6. A structure as specified in claim 1 in which said recess bottom is provided with a boss, said boss having a peripheral edge abutting the inner periphery of the beaded side wall of said domed ear, thereby holding said flattened bead against inward movement from said side wall of said recess.

15 7. A structure as specified in claim 1 in which said depressed portion of said body blank is provided with a curved fillet at the juncture of said bottom and side wall, said fillet conforming to and tightly contacting with said transversely curved peripheral edge of said flattened bead, said recess bottom being provided with a boss, said boss having a peripheral edge abutting the inner periphery of the beaded side wall of said domed ear, thereby holding said flattened bead against inward movement from said fillet.

20 8. A structure as specified in claim 1 in which said recess bottom is provided with a boss, said boss having a peripheral edge abutting the inner periphery of the beaded side wall of said domed ear, thereby holding said flattened bead against inward movement from said side wall of said recess, said acutely angled side wall opposing said boss and surrounding the same in concentric relation to cooperate therewith in forming a restricted channel in which the flattened bead is locked against displacement.
